(57) **CLAIM**

The ornamental design for a compressor assembly, as shown and described.

DESCRIPTION

FIG. 1 is a front, right side perspective view of a compressor assembly showing my new design;

FIG. 2 is a front elevational thereof;

FIG. 3 is a left side elevational view thereof;

FIG. 4 is a rear elevational view thereof;

FIG. 5 is a right side elevational view thereof;

FIG. 6 is a top plan view thereof; and,

FIG. 7 is a bottom plan view thereof.

In FIGS. 1-7, the broken line immediately next to the structure line represents the bounds of the design. All other broken line matter represents environment. None of the broken lines form any part of the claimed design.
